DESIGN FOR SUNGLASSES

Archibald Brock, Arlington, and Wesley H. Backer, Orange, N. J., assignors to The Eme-loid Company, Inc., Arlington, N. J.

Application December 6, 1938, Serial No. 81,604.

Term of patent 3½ years

To all whom it may concern:

Be it known that we, Archibald Brock and Wesley H. Backer, citizens of the United States, residing at Arlington, in the county of Hudson and State of New Jersey, and at Orange, in the county of Essex and State of New Jersey, respectively, have invented a new, original, and ornamental Design for Sunglasses, of which the following is a specification, reference being had to the accompanying drawing, forming part thereof.

Figure 1 is a front elevation of sunglasses the temples being omitted for convenience of illustration, showing our new design.

We claim:

The ornamental design for sunglasses, as shown and described.

ARCHIBALD BROCK.
WESLEY H. BACKER.
